CYLINDER LOCK

Theofilo Patrignani, Lecco, Italy

Application May 7, 1947, Serial No. 746,472
In Italy June 5, 1946

4 Claims. (Cl. 70—360)

1

This invention relates to a combination lock which is of increased safety and strength as compared with locks of the so-called Yale type embodying spring pins.

The main characteristic feature of this lock consists in the fact that transverse shaped rings are freely mounted on the rotor for oscillation and displacement in any direction, said rings being guided in notches in the rotor and having an outer diameter which is substantially equal to the bore of the stationary cylinder of the block in which the rotor is mounted, the above mentioned outer diameter being but a few tenths of a millimeter smaller in size with respect to the cylinder bore.

The stationary cylinder is formed internally at each ring with a groove and the rotor is formed centrally with a longitudinal shaped recess cooperating with radial shaped ribs on the key. Balls are mounted in radial seatings in the rotor and roll underneath the rings, said balls cooperating with the profile of the ribs on the key. The key is of such shape with respect to the inner shape of the rings which are acted upon by the balls pushed by the key, that only when the proper key is pushed home in the due direction, the rings are exactly centered by means of the balls on the rotor and the latter may be pushed in an axial direction, releasing it from a stop tooth which kept it from rotating with respect to the stationary portion. The axial displacement takes place against the action of a spring and in the axially displaced position the rotor, being released from the catch, may rotate and operate the lock.

By this device a very large number of combinations may obviously be obtained, which result in an increased safety. The parts are tough in construction and not easily damaged, and no sensitive springs as in the Yale locks are employed.

The accompanying drawing shows diagrammatically by way of example a construction of a lock block according to this invention.

Figure 1 is an axial section thereof, the key being properly fitted in so that the rings are perfectly centered, while the rotor has not yet been axially displaced.

Figure 2 shows a detail of the stationary block portion in axial section;

Figure 3 shows a detail of the rotor in axial section;

Figure 4 is a cross sectional view of the rotor;

Figure 5 is a plan view of the rotor;

Figure 6 is a detailed end view of the device 55

2

locking the rotor to the stationary portion, the parts being disengaged by the axial displacement of the rotor,

Figures 7, 8, 9 and 10 are detail views of four adjustable rings with which the rotor is provided.

1 denotes the stationary block portion, 2 denotes the rotor. The stationary portion 1 is formed in front with a circular hole 3 receiving the cylindrical collar 4 of the rotor, having a notch for the passage of the key 16. In the example shown the key has four shaped ribs 5; consequently, the notch in the key-hole is cross-shaped. The rotor is formed with radial openings 6 receiving balls 6' which may be displaced in a radial direction. A ring 7 is arranged over each transverse set of openings 6 and cooperating balls 6', the ring outer diameter matching the cylindrical bore of the stationary block portion 1. Each ring is provided with a radial catch 8 turned inwardly, which is held between two wires 9 stretched longitudinally between the end flanges 10 of the rotor, by which the rotor is guided within the stationary portion 1. The rings 7 may obviously be displaced and adjusted in any direction by effect of the profile of the ribs 5 on the key 16 when the latter is fitted into the key-hole.

The profile of each rib is designed in such manner with respect to the inner shape of the rings 7 that the latter are properly centered on the rotor axis when the key is pushed home in the key-hole.

The rings 7 that were held in the inner grooves 18 in the stationary block portion, are released therefrom so that, on pushing the key forward, the latter may displace the rotor axially releasing its catch 11 from the notch 12 in the stationary portion in which it was retained under the action of the spring 13. The extension 14 of the rotor then operates the lock in the known manner as, when the key is pressed and the teeth 11 and 12 are out of engagement, the rotor is free to rotate. On withdrawal of the key, the spring 13 pushes back the rotor to its normal position and the rings fall back into the grooves 18 in the stationary portion 1 in a relative position which is variable according to the adjustment of the block with respect to a vertical line.

It will be understood that I do not desire to be limited to the exact details of construction as described, for obvious modifications will occur to a person skilled in the art.

What I claim is:

1. In a lock, a tubular body having a set of

annular grooves formed in the inner surface of said body, an inner member rotatably supported in said body, means for securing the inner member to the tubular body in order to prevent its rotation, said securing means being disengageable only by axial displacement of the inner member, said inner member having an axial notch for the introduction of a key, said inner member having radial openings connected at their inner ends with the key notch, said openings being opposite the grooves of the inner periphery of the tubular body and the number of said openings opposite to each groove being equal to the number of indented profiles of the key, spacing members arranged inside said openings, rings situated in radial planes, and interposed between the inner member and the grooves of the outer body and having an outer diameter equal to the tubular body inner diameter, means for preventing rotation of said rings relatively to the inner member, the inner surface of each ring being of such a profile that only when the appropriate key is introduced into the axial notch of the inner member, the key indentations opposite the openings cooperating through the spacing elements with the inner surface of the rings, carry said rings into such a position that the axis of said rings coincides with the axis of the inner member, so that an axial displacement of the inner member can take place thus disengaging the securing means and permitting the rotation of said member relatively to the body.

25
30

2. A lock as claimed in claim 1, in which the means for preventing rotation of the rings relatively to said inner member are constituted by wires stretched parallel to the axis of the inner member and secured to end flanges of the inner member, the inner peripheries of said rings being formed with grooves and said wires passing in said grooves of said rings.

3. A lock as claimed in claim 1, in which each of the spacing members arranged inside the radial openings is constituted by one ball, said balls serving also to facilitate the introduction and withdrawal of the key.

4. A lock, as claimed in claim 1, in which the means for preventing rotation of the inner member are constituted by a catch fixed to the inner member, said catch being seated in a notch in the stationary block, and a spring maintaining said catch in the engaged position.
